DESIGN FOR A PIANO CASE

Gardner C. Kavanagh, Rochester, N. Y., assignor
to Aeolian American Corporation, East Roches-
ter, N. Y., a corporation of New York

Application August 8, 1935, Serial No. 58,018

Term of patent 14 years

To all whom it may concern:

Be it known that I, Gardner C. Kavanagh, a citizen of the United States, residing at Rochester, in the county of Monroe and State of New York, have invented a new, original, and ornamental Design for a Piano Case, of which the following is a specification, reference being had to the accompanying drawing, forming part thereof.

Figure 1 is a front elevation of a piano case showing my design, and Figure 2 is an end elevation.

The design comprises a rectangular key and action case supported on four legs arranged at the corners thereof, with a pedal support depending therefrom, and a vertical string case arranged at the rear thereof and projecting upwardly therefrom.

I claim:

The design for a piano case substantially as shown and described.

GARDNER C. KAVANAGH.
